Ezra Ripley (Assignor of Johnson & Co) Troy, N.Y.
Letters Patent (Design No. 111) dated 27th February, 1847.

The schedule referred to in these Letters Patent and
Ring, part of the same.

To all to whom these presents shall come; Be it known that I

Ezra Ripley of the City of ~~new~~, County of Oneida, and State of New York has invented a product a new design for stone plates, and that the following is a full clear and exact description of the same, reference being had to the accompanying drawings, making part of this specification in which representations Nos. 1 and 2 are views of said plates. The design of said stone plates are of bold configurations and the wholes work on the face of said plates present the appearance of an ornamental bracket of an entire fancy device. A plain oval sprung molding marked A is shown at the top edge of said plates, and immediately under said molding commences the bracket, which is ornamented with bold fancy scroll, leaf and diamond work, diminishing downward and terminating near the bottom of said plates.

No 1 is the front plate and No 2 the end plate both of which are ornamented with nearly the same fancy device.

I claim as my design for stone plates the above described and illustrated patterns and design to secure the same by Letters Patent.
